DESIGN FOR A BROILER GRILL

Stanley H. Hobson, Rockford, Ill., assignor to Gee. D. Reper Corporation, Rockford, Ill., a corporation of Illinois

Application March 16, 1940, Serial No. 99,982

Term of patent 7 years

To all whom it may concern:

Be it known that I, Stanley H. Hobson, a citizen of the United States, residing at Rockford, in the county of Winnebago and State of Illinois, have invented a new, original, and ornamental Design for a Broiler Grill, of which the following is a specification, reference being had to the accompanying drawing, forming part thereof.

In the drawing:

Fig. 1 is a plan view of a broiler grill, showing my new design, and

Figs. 2 and 3 are longitudinal sections taken on the lines 2—2 and 3—3 of Fig. 1.

I claim:

The ornamental design for a broiler grill, substantially as shown.

STANLEY H. HOBSON.
